(57) **CLAIM**

The ornamental design for a dishwasher, as shown and described.

DESCRIPTION

FIG. 1 is a front perspective view of the dishwasher showing our new design;

FIG. 2 is a front view thereof;

FIG. 3 is a back view thereof;

FIG. 4 is a left view thereof where the right view is a mirror image;

FIG. 5 is a top plan view thereof;

FIG. 6 is a bottom plan view thereof;

FIG. 7 is an enlarged view of a portion shown within the area designated as FIG. 7 in FIG. 1; and,

FIG. 8 is an enlarged view of a portion shown within the area designated as FIG. 8 in FIG. 1.

The broken lines depict portions of the dishwasher that form no part of the claimed design. The dash-dot broken lines are to show enlargement and form no part of the claimed design.

1 Claim, 8 Drawing Sheets
